(57) **CLAIM**

The ornamental design for flashlight, as shown and described.

DESCRIPTION

FIG. 1 is a perspective view of flashlight from right side showing my design;

FIG. 2 is a front side view thereof;

FIG. 3 is a left side view thereof;

FIG. 4 is a top elevation side view thereof;

FIG. 5 is a bottom elevation side view thereof;

FIG. 6 is a rear side view thereof;

FIG. 7 is a right side view thereof; and,

FIG. 8 is a perspective view of a second embodiment thereof, wherein the only difference resides in the flashlight lid.
